Filed Dec. 4, 1964, Ser. No. 82,919

Term of patent 3½ years

(Cl. D55—1)

FIG. 1

FIG. 2

FIG. 3

FIG. 4

FIG. 5

FIG. 1 is a top view of a vacuum forming machine showing my new design,

FIG. 2 is a front view,

FIG. 3 is a rear view,

FIG. 4 is a view of FIG. 1 from the right side thereof, and

FIG. 5 is a view of FIG. 1 from the left side thereof.

It is to be understood that the full line showing of the vacuum line in FIGS. 1, 2 and 4 is repeated throughout the broken line area thereof and the fragmentary showing of the line and electric cord in FIGS. 1, 3 and 5 is for convenience of illustration.

I claim:

The ornamental design for a vacuum forming machine, substantially as shown and described.
